(57) **CLAIM**

The ornamental design for a tool holder with bracket, as shown and described.

DESCRIPTION

FIG. 1 is a front and left-side perspective view of a tool holder with bracket showing our new design;

FIG. 2 is a rear and left-side perspective view of thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top-end view thereof; and,

FIG. 8 is a bottom-end view thereof.

The broken lines in the drawings are used to illustrate unclaimed portions of the tool holder with bracket and form no part of the claimed design.
